UNITED STATES PATENT OFFICE.

ANSON J. BENTLEY, OF NILES, OHIO.

FREEZING CAN.

Original application filed December 27, 1920, Serial No. 433,163. Divided and this application filed April 23, 1922. Serial No. 557,145.

To all whom it may concern:

Be it known that I, ANSON J. BENTLEY, a citizen of the United States, and a resident of the city of Niles, in the county of Trumbull and State of Ohio, have invented an Improvement in Freezing Cans, of which the following is a specification.

The present invention relates to improvements in freezing cans for use in the manufacture of ice and particularly to an improved construction of can wherein means are provided for introducing air into the can to agitate the water which is to be frozen; this being the commonly accepted practice in what is known as the raw water can system of ice making.

This application is filed as a division of an earlier application filed by me on December 27, 1920, Serial No. 433,163. That application showed several embodiments of the invention disclosed therein and the present application will be confined to one of those embodiments. The claims appended hereto will be directed to the particular embodiment of the invention shown herein; the invention common to the several forms being claimed in the above mentioned application.

In the raw water can system of ice making it is customary to immerse freezing cans in an appropriate freezing solution such as brine, and circulate this freezing solution around the cans. In order that the impurities commonly present in water available for the manufacture of ice may not be frozen into the finished cake, the water is agitated during the freezing operation. This agitation may be effected by an air current and the action is such that the impurities are not frozen into the cake but are collected in the small amount of water which remains unfrozen in a pocket in the ice cake at the termination of the freezing period.

In order to introduce this air current it has been customary to provide some sort of a separable tube or pipe extending from the top edge of the can downwardly to a point at or near the bottom and there opening into the interior of the can. This tube or pipe was so arranged that its upper end could be connected with a source of compressed air and when the can was in use, air was forced through the tube out into the water, thus agitating it with the result above described. As pointed out in my earlier application, freezing cans so constructed have proved un-

satisfactory for several reasons. If the tube or pipe is located on the outside of the can it is apt to be jammed or torn loose or otherwise injured as the cans are being handled. The liability to injury of any exposed part of the can will be immediately apparent when it is borne in mind that these cans usually contain three hundred or more pounds of water or ice as the case may be. If the air tube is located inside the can it is very apt to be injured during the freezing of the water or to be torn loose when the ice cake is dumped out of the can.

It is an object of the present invention so to construct a freezing can that a conduit for the introduction of air may be provided without the use of the usual separate tube or pipe, thus providing a distinctly superior construction and at the same time effecting a substantial economy in manufacture.

The embodiment of the invention which has been made the subject matter of this application is shown in the accompanying drawings wherein,

Figure 1 is a perspective view of a freezing can illustrating a preferred form of the invention selected for this application,

Figure 2 is a similar view of the inside of the can shown in Figure 1,

Figure 3 is an enlarged perspective view showing the construction of the air conduit, and

Figure 4 is a similar view showing a slight modification.

The general construction of the freezing can shown herein may be that of Letters Patent No. 1,027,802, dated May 28, 1912, in so far as the formation of the side walls and the bottom and the joining of the several parts are concerned.

The can shown in the drawings may be conveniently made of two sheets of galvanized metal cut and properly shaped so that one sheet will form the side wall 1 and the end wall 2, while the other sheet will form the side wall 3 and the end wall 4. A third piece of sheet metal may be suitably cut and shaped to be assembled with the side walls and form the bottom 5 of the can.

It is usual in freezing can construction to locate the seams at diagonally opposite corners and with this in view the sheet forming wall 2 is extended and bent to overlap the side wall 3, while the wall 4 is similarly extended to overlap wall 1. It may be as-

sumed that it is desired to make only one air conduit and locate the same adjacent to the seam between walls 2 and 3 in that corner of the can. To provide the embodiment of the present invention shown in the accompanying drawings, the wall member 3 is formed with an extension 3' which is bent through an angle of approximately 45° , extends for a short distance in that direction and is again bent in the same manner so that, when assembled with the other wall member, a web portion 6 will extend across and be spaced from the corner formed by the short right angular extension of the 15 end wall 2. Thus a triangular conduit 7 extending from a point at or near the top of the can to a point at or near the bottom will be formed by the cooperating overlapped wall members. A suitable opening 20 8 for the escape of air to the interior of the can may be made by cutting away a part of the web 6 as in Figure 3 or by forming a hole 8' in the web and letting the web 6 extend to the bottom 5 of the can as 25 in Figure 4.

In order to fasten the side walls firmly together a group of rivets 9 may be passed through the wall 3 and right angle extension of wall 2 and another group 10 through the 30 wall 2 and the margin of the extension of the wall 3. If two separate members are used in making the side walls of the can, another group of rivets 11 will be used. These riveted seams may be rendered fluid 35 tight by soldering in the usual manner.

Thereafter the bottom of the can may be assembled with the side walls and suitably riveted and soldered in place. A reinforcing band 12 may be placed around the top of 40 the can in the usual manner and riveted securely.

An appropriate fitting, designed to cooperate with the particular system in which the can is to be used, may be suitably attached 45 at the upper opening of the air conduit.

It will be observed that the construction herein shown and described provides a very durable means of introducing air into the can. The walls of the air conduit are of the 50 same strength as the walls of the can itself and there is little danger of the conduit being injured so as to interfere with

the passage of air therethrough. Moreover, there is no tube or pipe exposed on the outside of the can.

55

It will be understood that the invention may be variously modified and embodied within the scope of the subjoined claims.

I claim as my invention:

1. A freezing can, for use in the manufacture of ice, substantially rectangular in cross section and having the adjacent edge portions of wall material overlapped and fastened on both sides of a corner and spaced at the corner to form an air conduit integral 65 with the walls of the can.

2. A freezing can for use in the manufacture of ice having an air conduit extending from the upper edge thereof to a point near the bottom, said conduit being 70 formed by an integral extension of a wall member across a corner of the can between two groups of fastening means and partially spaced from the adjacent wall.

3. A freezing can for use in the manufacture of ice having a fluid tight lap seam formed in one wall adjacent a corner of the can and an integral portion of the overlapped wall material extended beyond the corner and joined to the adjacent wall, the 80 overlying wall material being partially spaced to form an integral air conduit.

4. A freezing can for use in the manufacture of ice having a lap seam formed adjacent a corner and an air conduit formed 85 in the corner by a diagonal extension of an inner wall member from said lap seam across the corner to the adjoining wall member.

5. A sheet metal container substantially 90 rectangular in cross section having an air conduit formed adjacent one corner thereof by an integral extension of the material of one wall beyond the corner to the adjoining wall, means joining together the overlapping 95 wall material on each side of the corner and means providing an opening from the conduit to the interior of the container near the bottom thereof.

In testimony whereof, I have signed my 100 name to this specification this 24th day of April, 1922.

ANSON J. BENTLEY.
